(57) **CLAIM**

The ornamental design for a near-field communication enabled smart device, as shown and described.

DESCRIPTION

FIG. 1 is a rear view of a first embodiment of the near-field communication enabled smart device, showing our design; FIG. 2 is a top view thereof, the bottom view being identical to the top view;

FIG. 3 is a left side view thereof, the right side view being a mirror image of the left side view;

FIG. 4 is a front view thereof, and,

FIG. 5 is a rear view of a second embodiment of the near-field communication enabled smart device.

The dash-dash-dash broken lines represent environment and form no part of the claimed design. The dash-dot-dash broken lines represent the boundary of the claim.
